CLAIM

The ornamental design for a point of sale station, as shown and described.

DESCRIPTION

FIG. 1 is a perspective view of a point of sale station showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the point of sale station that form no part of the claimed design. The unshaded areas adjacent to the solid lines form no part of the claimed design.

1 Claim, 7 Drawing Sheets
